UNITED STATES PATENT OFFICE

JACOB TELLER, OF NASHVILLE, TENNESSEE, ASSIGNOR OF ONE-HALF TO WILLIAM A. GRISWOLD, OF NASHVILLE, TENNESSEE

HEATER

Application filed February 12, 1929. Serial No. 339,360.

The present invention relates to improvements in heaters and more particularly to a heater that is designed to employ gas as a fuel.

5 One of the important objects of the present invention is to provide a gas heater that includes a casing within which is arranged a series of vertically disposed air tubes open at their upper and lower ends, the products 10 of combustion being adapted to circulate around the air tubes for heating the air passing upwardly therethrough, additional means being arranged within the casing to effect the circuitous flow of the products of combustion around the air tubes.

Another important object is to provide a heater of the above mentioned character wherein heat radiating fins are associated with each air tube.

20 Another object is to provide a gas heater of the above mentioned character wherein the gas burner is provided with supplemental air passages that are arranged concentrically with respect to the gas discharge orifices 25 formed in the pipe of the burner.

Still a further object is to provide a gas burner of the above mentioned character that will at all times be positive and efficient in its operation, the same being further simple 30 in construction, inexpensive, strong and durable and further well adapted to the purposes for which it is designed.

Other objects and advantages will become apparent during the course of the following description.

In the accompanying drawing, forming a part of this specification, and in which like numerals indicate like parts throughout the same:

40 Figure 1 is a vertical sectional view through the gas heater embodying my invention;

Figure 2 is a sectional view taken approximately on the line 2—2 of Figure 1 looking in the direction of the arrows;

45 Figure 3 is a sectional view taken approximately on the line 3—3 of Figure 1 looking downwardly;

Figure 4 is a similar section taken substantially on the line 4—4 of Figure 1 also looking 50 downwardly;

Figure 5 is a transverse section taken substantially on the line 5—5 of Figure 1 looking in the direction of the arrows, and

Figure 6 is a sectional view taken approximately on the line 6—6 of Figure 4.

In the drawings wherein for the purpose of illustration is shown the preferred embodiment of my invention, the numeral 1 designates a substantially rectangular shaped casing that is open at its top and bottom.

Suitable supporting legs 2 space the open lower end of the casing from the ground as suggested in Figure 1. A grating 3 is arranged on the top of the casing.

The lower portion of the front side of the 65 casing is set inwardly as indicated at 4 in Figure 1 and a swinging door 5 is associated with this set in portion and radiant tiles 6 are mounted in the door in the manner well known in the art. It will also be observed 70 that upon referring to Figure 1 that the door 4 when in a closed position is disposed at an incline and above the burner a unit denoted generally by the reference character 7.

This burner unit includes a base plate 8 75 on which is arranged the longitudinally extending gas chamber 9 that is of substantially rectangular configuration and cross section as clearly indicated in Figure 6. The top of the gas chamber 9 is formed with the 80 gas discharge openings 10, the same being arranged in staggered relation as more clearly shown in Figure 4.

This gas chamber 9 extends upwardly 85 through the bottom of the casing for disposition within the lower front portion of the casing and the base plate 8 engages with the adjacent portion of the bottom of the casing as clearly indicated in Figures 1 and 6. The gas chamber 9 extends for substantially the 90 entire length of the casing and a gas pipe 11 has connection with one end of the gas chamber 9, the other end of this gas pipe having connection with a suitable source of gas supply not shown.

95 This burner unit further includes the provision of air tubes 12 that extend vertically through the gas chamber 9, the lower ends of these air tubes projecting through openings formed in the base plate 8 while the 100

upper ends are disposed through the respective gas outlet openings 10 as also clearly shown in Figure 6. The air tubes 12 are of a smaller diameter than the gas outlet openings 10 and the gas emitted through the openings 10 commingles with the air discharged from the upper ends of the respective tubes 12 to provide a blue flame when the burner is ignited.

10 A series of substantially rectangular shaped air tubes or flues 13 are arranged vertically in the rear portion of the casing, the same extending at the lower ends through the openings provided therefor in the bottom of the casing while the upper ends extend through similar openings provided therefor in the top of the casing and in the present instance, I have shown five of such air tubes or flues as being arranged within the casing 1, the 15 same being spaced with respect to each other.

Formed on the inner opposed faces of the longitudinal sides of each air flue are the vertically disposed radiating fins 14, the inner opposed edges of the respective pairs of fins 20 being spaced from each other as more clearly shown in Figures 4 and 5.

The purpose of these fins is also well known in the art and therefore detail description of the same is believed unnecessary. Forming 25 a salient part of the present invention are the horizontally disposed baffle plates 15 that are arranged in vertically spaced relation within the casing 1 and upon referring to Figure 1 it will be observed that the lowermost baffle plate extends from the front side of the casing to a point adjacent the rear side thereof and the uppermost baffle plate extends from the rear side to a point adjacent the front side.

30 40 This is for the purpose of effecting a circuitous flow of the products of combustion around the air flues or tubes 13 before being discharged out of the casing through the outlet 16 provided at the upper portion of the rear side of the casing.

It is also to be understood that each baffle plate is cut out to accommodate the several vertically disposed air flues.

In Figure 1 there is shown by the arrows 35 how the products of combustion pass around the air flues and also the direction of the flow of the air through the flues 13 and obviously as the air passes upwardly through these flues, the same will be heated by the products of combustion and the heated air is emitted through the grading 3 arranged at the top of the casing.

40 It will thus be seen from the foregoing description, that I have provided a gas heater that will afford a maximum heating effect and the fins will further secure a maximum amount of radiation from the air flues. Also the air to be heated will not be contaminated 45 by any fuel gases and due to its simplicity, the

heater can be constructed at a very low cost and yet be strong and durable.

While I have shown the preferred embodiment of my invention, it is to be understood that various changes in the size, shape and arrangement of parts may be resorted to without departing from the spirit of the invention and the scope of the appended claims.

Having thus described my invention, what I claim as new is:

1. A heater comprising a casing having a door-supporting portion extending inwardly and upwardly at an inclination to the bottom of the casing, air flues extending longitudinally through said casing and spaced from said door supporting portion, a gas burner within the space between the said flues and said door supporting portion, and a door unit of radiant tiles mounted in said door supporting portion and adapted when in closed position to provide an inclined reflector above the burner.

2. A heater comprising a casing having a bottom burner receiving opening extending substantially the full width of the casing and adjacent one side thereof and having the lower portion of said side set inwardly to provide a door holding portion disposed above and inclined to the said burner receiving opening, a gas burner extending upwardly through said bottom opening for substantially the full length thereof, a series of relatively spaced air tubes extending vertically through the said casing and arranged in a row parallel to the said opening, said air tubes being rectangular in cross section and respectively disposed with their lower ends at right angles to said burner, a horizontally disposed baffle integrally connected to a side of the said casing above the said intake portion and terminating in spaced relation to the opposite side of the casing, said baffle being cut out to accommodate the several air tubes, and a door mounted in said door holding portion and inclined therewith, said door

having a radiant deflecting face above the said burner for deflecting the heated gases transversely between the said air tubes.

In testimony whereof I affix my signature.

JACOB TELLER.
